FRATERNAL PLAQUE

Edith M. Thomson and Alfred P. Thomson, both of 900 SW. 29th St., Fort Lauderdale, Fla.

Filed Apr. 25, 1960, Ser. No. 60,294

Term of patent 14 years

(Cl. D29—23)

FIG. 1

FIG. 2

FIG. 4

We claim:

The ornamental design for a fraternal plaque, as shown.
